UNITED STATES PATENT OFFICE.

WILLIAM D. CARSON, OF CENTRALIA, ILLINOIS.

STACK-COVERING.

SPECIFICATION forming part of Letters Patent No. 748,701, dated January 5, 1904.

Application filed April 9, 1903. Serial No. 151,924. (No model.)

To all whom it may concern:

Be it known that I, WILLIAM D. CARSON, of the city of Centralia, Marion county, State of Illinois, have invented certain new and useful Improvements in Stack-Coverings, of which the following is a full, clear, and exact description, reference being had to the accompanying drawings, forming a part hereof.

My invention relates to improvements in stack-coverings, and has for its object to provide means whereby stacks of straw or similar commodities may be quickly and effectually provided with adjustable covering.

In the accompanying drawings, which form a part of this specification, Figure 1 represents the under view of a stack provided with a covering of my invention. Fig. 2 is an end view of a section of the covering. Fig. 3 is a perspective of a section of the upper side of the covering. Figs. 4 and 5 are details of construction.

My straw-stack covering consists of a series of planks A, intended to be held superimposed longitudinally. Each of the planks A is provided with a series of longitudinal slots B. Upon each side of the stack C the posts D are provided with the notches E and are planted in the ground. The planks A are held together and in position by means of the chain E', which is provided at each end with a link F. Beneath each of the planks A the

chain E' is provided with a plate G, provided with lug H. Each of the planks A is then adjusted in position upon the chain E and over the stack C by imposing the slot B over the lug H, so that the lug H extends vertically through the slot B when the plank A is turned into position shown in Fig. 3, so that the lug H will be in transverse position, thereby holding the plank A firmly in place. By means of the links F of the chain E' and planks A may be tightened or released at will through the adjustment of the links F in the notches E.

Having thus described my invention, what I claim as new, and desire to have secured to me by grant of Letters Patent, is—

A device of the class named consisting of planks provided with slots, a chain provided with plates and with lugs, the lugs adapted to engage with the slots in the planks, posts embedded in the ground at either side of the stack and provided with notches, links at each end of the chain adapted to engage with the notches on the post, substantially as and for the purposes specified.

In testimony whereof I affix my signature in presence of two witnesses.

WILLIAM D. CARSON.
